FOREIGN PATENT DOCUMENTS

JP 2019010447 A * 1/2019

Primary Examiner — George D. Kirschbaum*Assistant Examiner* — Calvin E Vansant(74) *Attorney, Agent, or Firm* — Fitch, Even, Tabin & Flannery LLP(57) **CLAIM**

The ornamental design for a hand warmer, as shown and described.

DESCRIPTION

1. Hand warmer
- 1.1 : Perspective
- 1.2 : Front
- 1.3 : Top
- 1.4 : Right
- 1.5 : Back
- 1.6 : Bottom
- 1.7 : Cross sectional
- 1.8 : In-use view for reference

The left view is omitted because it is a mirror image of the right view; reproduction 1.7 shows the cross-sectional view

(Continued)

taken along line A-A in reproduction 1.2; the thin lines on the article in reproduction 1.1 shows a three-dimensional shape of the article surface.

1 Claim, 8 Drawing Sheets
